PASSENGER CARRIAGE FOR SKI OR LIKE
ELEVATED WAYS

George W. Morton, Bartlett, N. H.

Application March 23, 1939, Serial No. 263,758

4 Claims. (Cl. 104—140)

My present invention is directed to improvements of my invention set forth in pending application Serial No. 229,107, filed September 9, 1938, and particularly to the development of 5 fore and aft safety factors by which my passenger carriages or cars are progressed more steadily with reference to their draft axis and by which their performance on both straight track and curved turn is made more uniform in spite of 10 variant conditions on the elevated way of collections of ice or snow.

In order to bring my inventions up to their actual operating service, I set forth herein certain improvements which have been found 15 wholly practical and demonstrate the basis by which similar installations can be improved in their operation.

Throughout the specification and drawings like reference characters are employed to indicate corresponding parts, and in the drawings:

20 Fig. 1 is a general view of a ski passenger carriage and fragmentary suggestive indication of a section of its immediately related cooperating installation.

25 Fig. 2 is a plan view of the running gear of a car with its platform only indicated by broken lines to give the relative relations.

Fig. 3 is a side elevation of an improved towing arm according to my present invention.

30 Fig. 4 is a face view of the same.

Fig. 5 is the rear arm in front elevation.

Fig. 6 is a side elevation of the same.

Fig. 7 is a bottom view of the member, and

35 Fig. 8 is a partial vertical longitudinal section-al view through a car and a section of inclined elevated cable way.

It will be understood that the fragment of way indicated in the drawings at W—W is part of a system according to my invention. One of its 40 characteristics is that its towing cable C is, between its turns, supported by my carriages. Of these I provide a plurality and preferably enough to provide for the arrival of a car at a station at intervals of a few minutes according 45 to the terrain as engineered and the numbers of the public served.

The matter of suspension and freedom of run 50 of the cable C is important because of the weight of the cable itself, which is usually a twisted steel factor, and makes all irregularities in towing a serious loss in power and efficiency. However, as ice and snow are importantly present in skiing season cars encounter considerable irregularities 55 on the way surface in spite of the degree of

efficiency of my brush or scraper members which keep the way clear.

The relation of the wheel systems of carriages A according to my invention, which consist of a front and rear axle and preferably rubber tired 5 wheels makes their performance vital to success. This is true in taking the turns at top and bottom as well as in the straight sections which constitute the major problem especially on the up-way where the cars are usually loaded.

The cross linking of the front and rear axles D as indicated at E' makes for smooth traction, but irregularities of the way surface and variations in load make consistent towing a difficult 10 service to attain.

One of my present concepts is that of an advanced guide for the front cable arm and a rear guide preferably disposed axially of the arc of turning movement of the rear or following 15 wheels.

Referring to Fig. 3 it will be seen that I have provided my front towing arm F with an offset or leading bracket I. These brackets I are in operation steering assistants for the front wheels of the cars being run on the way. These may be 20 proportioned to length of the car, the radius at turns, the spacing of cars along the cable in their supporting relation to it, according to the engineering problem of any installation, but in the form indicated it is in practice only a five inch 25 overhang on a way running sixty cars on an upward incline of several thousand feet usually inclined at about 15° or 20% incline.

In such a way the width of slot O of the way W will be varied according to local problems 30 and engineering design. In practice, in the way above mentioned, it is found very successful at a 1 1/2 inch spacing. It is just enough to give a free run and may be edge faced as at O' to get a harder strip than the edge of the way which 35 may be of planking of any available sort, even that of a utilization of the larger trees that occur in the proposed location of the way for sawing after clearing the way or cutting any other convenient timber as where vistas are to be provided more particularly for summer service. Such 40 an installation, if available to automobilists, attracts many sightseers regardless of their enthusiasm for skiing. Mountaineering is thus made possible to those who ordinarily would not be 45 physically able to stand even a relatively low climb with new views of ranges added to the attractions and justifying upkeep and operation even in the summer season.

Considered in its simplest aspects my con- 55

- cept provides for a carriage or system of carriages such as I have indicated generally in Fig. 1. In this view I have indicated generally as A a wheeled unit later to be described in one of its 5 preferred forms, but generally to be understood as a part of an inclined elevated cable system. I have suggested in fragment with the carriage A a pair of supporting ways W spaced slightly apart to leave an intermediate opening O.
- 10 Referring to the carriage A as the basis of consideration, I may at the outset call attention to the fact that the passenger seat S is askew of the cable or towing axis. It preferably is on the angle of seating incidence when considered 15 from the axis of the boarding rail R, R' by which the passenger swings aboard, having first stepped upon the running board inset U or which may extend the full length of the side of the carriage for summer service.
- 15 This rail (see Fig. 1) includes a main vertical stanchion portion R and its bracing cross rail portion R'. As indicated in the suggestion of the immediate installation, such a stanchion rail may be backed or braced on like guard rails G 20 which may be advisable for guarding passenger carelessness when in transit.

An actual embodiment may be several thousand feet in ascent and up any geographically favorable location, one such as might be indicated, as 25 for example, by a straight line on a contoured Survey-Map, showing the location, but it will be understood that any actual view is impossible except on a miniature or model basis. Only a single car is indicated in the view, but in practice they are continuously spaced along the cable.

That the showing be better understood and appreciated, it may be indicated that an actual present project involved an inclined way some three thousand feet in ascent. It is pitched to 40 a 15° or 20% incline. Including its return way, the so-called ways or walks W involve a length of some six thousand feet of elevated surface. This may be and preferably is in typical installations of plank and supported on posts, trestles, or other 45 convenient and inexpensive understructure.

Taking such an installation as illustrative, it will be seen that my invention provides for the support of the cable C intermediate the bottom 50 sheave and a top or driving sheave. Such drive sheave may be powered in any convenient and economical manner, as by a gasoline engine or electric motor, where such power is available. (Not shown.)

A bottom sheave is preferably mounted on 55 a car movable on tracks and counterweighted in the usual manner in cable ways of such types for taking up the slack due to varying loads.

Referring to Fig. 1, it will be seen that my carriage A can be in the form of simple wheeled 60 trucks in which the passenger platform as at A' (Fig. 8) is utilized as the longitudinal frame.

The axles D are pivoted as at E and are connected across as by the tie rod E' so that the wheels at front and rear turn at predetermined 65 angles as suggested in Fig. 2 as the carriage is drawn around its curved path above the periphery of the sheave.

As will be seen from Fig. 8, the carriages are towed by arms F which are hung on a pivoting 70 fork H on the front or leading axle of each carriage. At its lower end a yoke Y is pivoted as at X.

The yokes Y encircle members Z secured to the cable at regular intervals, as, for example, every 75 100 feet. This permits a free swiveling bearing

for the yoke which forms an offset pivoted foot for the bar F in passing around the groove sheaves as suggested in Fig. 1.

The wheels T are preferably rubber tired and thus have a firm bearing on the top of the walks 5 W which go to make up the way.

According to my concept this top surface is simply kept brushed free of loose snow by angularly disposed brushes K braced to the carriage front as at L, and slanted to move the snow 10 laterally away from the slot O. The wheels have suitable guards of any desired contour for non-resistance to wind or for comfort and safety of passengers.

In operation such an installation offers various 15 novel advantages, particularly for the ski-minded public. It may be said to provide a novel method of upgrade assisted progression of ski or like equipped passengers in which the procedure consists in mounting an upgrade moving conveyance 20 while standing beside its way, including the preliminary stage of assuming a mounting stance parallel to the movement of the conveyance, in making pivotal manual engagement with the conveyance laterally thereof, in shifting the 25 mounting stance laterally to the conveyance and in assuming a seated posture upon the conveyance.

According to my present invention, the towing arm F is provided with a vertical guide 2 supported on a short forwardly projecting bracket 1. This guide is a short cylindrical bar of slightly less diameter than the central slot or opening O in the way W.

It is set centrally under the yoke H which in 35 the form shown is made with its end brackets at right angles to the cross bar portion Y. This gives more perfect pivoting of the towing arm F in its pivoting mounting on the front axle D of each car.

The arm F is preferably bent from flat stocks 40 and has at its lower end a pair of overlapped fork forming members Y conveniently welded to the main or central arm F.

At the rear wheel axle of the carriage I provide a yoke. It preferably is formed from flat stock as a cross web 10 having upturned perforated ears 11. Centrally of this rear yoke I mount a cylindrical spur 12 which may be spot welded to the cross member 10 and works freely 50 in the slot O. By guiding the rear of the carriage in the axis of swing of the rear wheel axle lateral movements are promptly checked and the car thus kept under a steady control in spite of ice or other roughness on the way.

While I have laid opening emphasis on the 55 skiing aspects of my invention, it is of course as I have heretofore suggested a boon to mountain lovers who for lack of time or strength cannot make the grade on foot.

As the ski passenger so stands he or she faces 60 uphill or in the direction in which the carriages move in making the ascent. As the carriage comes abreast of the waiting passenger, the stanchion R or its rail R' is grasped while the left foot with or without its ski is slipped aboard the low plane of the running board U. As soon as weight can be transferred to the foot so positioned the other foot and its ski can be lifted to a place beside it when the passenger steadied 65 by the stanchion R and rail R' swings diagonally into the seat S which is skewed or angled comfortably to receive him.

When it is desired to dismount at the top or at some optional intermediate level, the passen- 70 75

ger simply rises from the seat S and holding the stanchion R and rail R' assumes a standing posture until first his right (or outside) foot takes the snow at the station side of the way. Then 5 when weight is put upon it, the other foot is taken from the running board U and its ski launched in running contact with the snow at the side of the way. The dismounted passenger thus arrives in balanced standing posture and 10 under the slight momentum of the carriage speed which is about four miles per hour.

In this way a miscellaneous passenger personnel without previous experience can handle it- 15 self without delay or mishap. As installations according to applicant's invention increase on standardized bases of control, the public will have a chance increasingly to become educated even when using an installation at a wholly new site, so that the service to such importantly in- 20 terested may become as it were institutionalized for the common good of all.

In my foregoing discussion, I have referred to my elevated structure as a way or ways. Preferably it is built as a pair of parallel plank 25 walks W spaced slightly apart to leave an intervening slot O beneath which the endless towing cable C runs being supported at intervals along its length by the towing arms F of the carriages themselves.

30 Adjacent the way at the lower and upper levels are mounting or dismounting platforms. Also as above suggested, it is desirable to provide intermediate sidings or take offs I leading from the main way or ways along which the carriages A 35 are being towed according to the terrain of the location selected for the side of any particular installation.

As before suggested, installations according 40 to my invention may be used in winter for skiing and in summer simply for giving passengers assistance to reach heights which would not otherwise be available to them or at least within the time at their disposal. In connection with the technique of the skiing practice this may be 45 varied according to the dexterity of the passenger or according to the ideas of the management as to what is best for handling crowds expeditiously and safely. In some instances the running board U may be dispensed with and the passengers board 50 the car by stepping directly on to the recessed floor of the platform A'. Where running boards are omitted, attendants may hand the passenger's skis strapped together to him or her after being 55 safely seated on the seat S. When dismounting at the other end, the skis may be passed to the attendant at that end so that the passenger has both hands free to grasp the rail R—R'. This 60 is of some assistance in the case of passengers who have not before mounted or dismounted from such moving carriages as go to make up the moving equipment of the installation.

In addition to my brush system K I may have 65 an auxiliary system K' placed at the rear of the carriage or some carriages may be equipped with front brushes and some with rear brushes to obtain variety in sweeping performance on the ways W. These brushes may be of fibre or metal or formed as scrapers according to the snow and ice conditions prevalent at any particular in- 70 stallation.

Such installations and modifications may and 75 probably will develop various nomenclatures but their structure and mode of operation are to be understood as within the purview of my invention if within the scope of the appended claims.

What I therefore claim and desire to secure by Letters Patent is:

1. A ski passenger carriage for skier's service on upgrade approaches to an elevated take-off along a cabled inclined way, said way having a 5 central slot and having an endless cable disposed to run below the plane of said slot, said carriage including a platform support, a wheel axle vertically pivoted beneath each end of said support, a depending towing arm dirigibly connected to the front axle of said carriage and disposable through the slot of said inclined cable way below the plane of the wheel axles and clamped to the cable, a forwardly projecting vertical guide on said depending towing arm and supported for free guidance in said slot in advance 10 of the towing cable connection, said axles being connected across so that the wheels at front and rear turn at predetermined angles. 15

2. A ski passenger carriage for skier's service 20 on upgrade approaches to an elevated take-off along a cabled inclined way, said way having a central slot and having an endless cable disposed to run below the plane of said slot, said carriage including a platform support, a wheel 25 axle vertically pivoted beneath each end of said support, a depending towing arm dirigibly connected to the front axle of said carriage and disposable through the slot of said inclined cable way below the plane of the wheel axles and 30 clamped to the cable, a forwardly projecting vertical guide on said depending towing arm and supported for free guidance in said slot, a rear 35 guide yoke mounted on the rear axle adjacent its center of turning, and a depending spur on said yoke supported for free guidance in the slot way, said axles being connected across so that the wheels at front and rear turn at predetermined angles.

3. A ski passenger carriage for skier's service 40 on upgrade approaches to an elevated take-off along a cabled inclined way, said way having a central slot and having an endless cable disposed to run below the plane of said slot, said carriage including a platform support, a wheel 45 axle pivoted beneath each end of said support, the front axle, at least, being pivoted about a vertical axis, a depending towing arm dirigibly connected to the front axle of said carriage and disposable through the slot of said inclined cable 50 way below the plane of the wheel axles and clamped to the cable, and a cylindrical forwardly projecting vertical guide on said depending towing arm and supported for free guidance in 55 said slot.

4. A ski passenger carriage for skier's service 60 on upgrade approaches to an elevated take-off along a cabled inclined way, said way having a central slot and having an endless cable disposed to run below the plane of said slot, said carriage including a platform support, a wheel axle pivoted beneath each end of said support, the 65 front axle, at least, being pivoted about a vertical axis, a depending towing arm dirigibly connected to the front axle of said carriage and disposable through the slot of said inclined cable way below the plane of the wheel axles and clamped to the cable, a cylindrical forwardly projecting vertical guide on said depending towing arm and supported for free guidance in said slot, 70 a rear guide yoke mounted on the rear axle adjacent its center of turning, and a depending spur on said yoke of cylindrical cross section and supported for free guidance in the slot way. 75
